JOHN F. TOOMEY, OF NEW YORK, AND CHARLES S. DEMAREST, OF BROOKLYN, NEW YORK, ASSIGNORS TO AMERICAN TELEPHONE AND TELEGRAPH COMPANY, A CORPORATION OF NEW YORK.

REPEATER-NETWORK-SELECTING APPARATUS.

1,880,751.

Specification of Letters Patent. Patented June 7, 1921.

Application filed July 9, 1919. Serial No. 309,595.

To all whom it may concern:

Be it known that we, JOHN F. TOOMEY and CHARLES S. DEMAREST, residing at New York and Brooklyn, in the counties of New York and Kings, respectively, and State of New York, have invented certain Improvements in Repeater-Network-Selecting Apparatus, of which the following is a specification.

10 This invention relates to telephone repeaters and more particularly to the arrangements for controlling the selection of the requisite electrical networks for balancing the transmission lines that may be connected with the repeater.

15 In order that a telephone repeater may operate properly, it is necessary to provide an electrical network or a group of such networks to balance the line and such auxiliary apparatus that may be connected therewith. It is customary in long distance telephony to use the physical circuits not only for purposes of telephony, but also to provide telegraph circuits; and, moreover, groups of 20 physical circuits are frequently combined in order to provide phantom telephone circuits. In order that these physical circuits may 25 perform these various functions, it is necessary to connect with the physical circuits various types of auxiliary apparatus such as composite sets, composite ringers and phantom coils. When such circuits have a 30 telephone repeater connected to them it is necessary in order that the repeater may 35 function properly to connect into the repeater circuit a group of electrical networks, each of which has the same impedance characteristic as a part of the transmission circuit which the entire group of networks is 40 intended to balance.

When a telephone repeater, having associated with it a group of networks, as described above, is connected to a line having corresponding auxiliary apparatus, a balanced condition exists and the repeater will operate properly. If, however, the auxiliary apparatus, or some part thereof, as for example the composite apparatus, which adapts 45 the physical circuit for combined telephone and telegraph purposes, should be removed from the line circuit, the repeater would not

be properly balanced unless the composite balancing network were disconnected from the repeater circuit. It is one of the objects of this invention to provide simple means 55 for disconnecting a balancing network whenever the corresponding auxiliary apparatus is removed from the line. Further objects of this invention will be apparent from the following description when read in connection with the accompanying drawing, the figures of which when Fig. 2 is placed in juxtaposition to the right of Fig. 1 constitute a circuit diagram of one embodiment of the invention.

65 In the drawing L_1 and L_2 represent two physical circuits extending in one direction from a repeater station and having superimposed thereon phantom circuit L_5 . L_3 and L_4 represent two other physical circuits extending in another direction from the said repeater station having superimposed thereon a phantom circuit L_6 . The circuits L_1 , L_2 , and L_5 are connected with the circuits L_3 , L_4 , and L_6 , respectively, by means of the 70 repeaters R_1 , R_2 , and R_3 , respectively. Associated with each of the lines L_1 , L_2 , L_3 , and L_4 is a composite set X_1 , X_2 , X_3 , and X_4 , respectively, and also phantom coils C_1 , C_2 , C_3 , and C_4 , respectively. Each composite 75 set is provided with a group of jacks, by means of which the said set may be dissociated from the line whenever the plugs which are adapted to coöperate with the said jacks are inserted therein.

85 Repeater R_1 , which connects lines L_1 and L_3 , comprises two repeater elements A_1 and A_2 , and a group of networks CN_1 , XN_1 , and LN_1 adapted to balance line L_1 and its auxiliary apparatus, and networks CN_3 , XN_3 , 90 and LN_3 adapted to balance line L_3 and its auxiliary apparatus. Networks LN_1 and LN_3 have the same impedance characteristics as the lines L_1 and L_3 , respectively. Networks XN_1 and XN_3 have the same characteristics as the composite sets X_1 and X_3 , respectively, and the networks CN_1 and CN_3 have the same characteristics as the phantom coils C_1 and C_3 , respectively.

95 The repeater R_2 is similar in arrangement 100 to the repeater R_1 and the networks associated therewith are adapted to balance the

lines L_2 and L_4 and associated apparatus. Repeater R_3 , which is adapted to connect the phantom line L_5 with the phantom line L_6 , is similar in arrangement with repeaters R_1 and R_2 . The networks LN_5 and LN_6 , associated with repeater R_3 are adapted to balance the phantom circuits L_5 and L_6 respectively, the networks XN_5 and XN_6 and the networks CN_5 and CN_6 are adapted to balance the repeater circuit R_3 against the effect of the composite sets and the phantom coils in the side circuits of the phantom circuits L_5 and L_6 , respectively.

This invention will be more fully understood from a description of its mode of operation. If all of the auxiliary apparatus is connected with the lines as shown in the drawing, all of the networks shown will be effectively connected with the repeater circuits, so as to balance the lines and their associated apparatus. If, however, it becomes necessary to disconnect the composite set X_1 from the line L_1 on account of injury to the composite set, or for any other reason, the plug P_1 is inserted in the jack J_1 and plug P_2 inserted in jack J_2 , thereby establishing a circuit from battery B_1 , relays S_1 and S_2 , conductor 1, contacts of plugs P_1 , and P_2 , and jacks J_1 and J_2 , respectively, in parallel, upper normal contact of jack J_{11} to ground. Relays S_1 and S_2 are thereby operated, disconnecting the network XN_1 from the group of networks adapted to balance the line L_1 and its associated apparatus. The remaining networks LN_1 and CN_1 will balance the line L_1 and the phantom coil C_1 , and therefore the repeater circuit remains balanced.

When the composite apparatus is removed from one of the side circuits of a phantom circuit, it is customary in order to maintain balanced conditions to remove the corresponding composite apparatus from the other side circuit. Accordingly plugs P_3 and P_4 would be inserted in jacks J_3 and J_4 , respectively, thereby effectively removing the composite set X_2 from the line L_2 and establishing a circuit from battery B_2 , relays S_3 and S_4 , conductor 2, contacts of plugs P_3 , P_4 , and jacks J_3 , J_4 , respectively, in parallel, and the upper normal contact of jack J_{12} to ground. Relays S_3 and S_4 are thereby operated, thus disconnecting composite network XN_2 from the group of networks with which it is associated. Line L_2 and its phantom coil C_2 are therefore balanced by networks LN_2 and CN_2 , so that the repeater will operate properly.

When the composite sets are removed from the side circuits of the phantom, it is, of course, necessary that the network associated with the phantom repeater and which is adapted to balance the effect of the composite sets upon the phantom circuit should be removed from the phantom balancing networks. When relays S_2 and S_4 are oper-

ated as the result of the removal of the composite sets X_1 and X_2 , contacts 3 and 4, respectively, were closed, thereby establishing a circuit from battery B_3 , relays S_5 and S_6 , conductors 5 and 6 in parallel to ground. As a result of the operation of relays S_5 and S_6 , the composite balancing network XN_5 is removed from its associated networks and the remaining networks LN_5 and CN_5 are adapted to balance the phantom circuit when the composite sets X_1 and X_2 have been disconnected.

In a similar manner the networks XN_3 , XN_4 , and XN_6 may be disconnected from their respective repeater circuits whenever composite sets X_3 and X_4 are disconnected. The phantom balancing networks CN_1 , CN_2 , CN_5 and CN_3 , CN_4 , CN_6 are shown permanently connected in the balancing circuit since, in practice, the phantom coils are seldom disconnected from the line. And, furthermore, this principle and the means for applying it are applicable to any type of auxiliary apparatus and its corresponding network.

If a composite set, as for example X_1 , which is ordinarily associated with line L_1 , has become defective so as to necessitate its removal from the line and it is desired to maintain telegraphic service, the plug of a portable composite set may be inserted in the jack J_{11} , and a corresponding plug at the other end of the said portable composite set in the jack J^{15} . By the insertion of the plug of the portable composite set in the jack J_{11} , the ground is removed from the circuit of the relays S_1 and S_2 by the opening of the upper normal contact of jack J_{11} . As a result relays S_1 and S_2 are prevented from operating when the set X_1 has been replaced and the network XN_1 remains in the repeater balancing circuit in order to balance the portable composite set that has been temporarily connected with the line L_1 in place of composite set X_1 . Furthermore, relays S_5 and S_6 are not operated, so that the composite balancing network XN_5 associated with the phantom repeater likewise remains connected with its said repeater circuit.

It will be seen, therefore, that this invention provides simple means for disconnecting a balancing network from a telephone repeater circuit whenever its corresponding auxiliary apparatus is disconnected from the line circuit. As a result, only such networks will be connected as are necessary to balance the line and such auxiliary apparatus as may be connected with said line, so that repeater will always be in a balanced condition and, therefore, will operate properly.

Although this invention has been shown as embodied in a particular form, it is understood that it is capable of embodiment

in other and different forms without departing from the scope of the following claims.

What is claimed is:

5. 1. In a telephone transmission system, the combination of a transmission line, auxiliary apparatus associated with said line, a telephone repeater permanently connected with said line, a group of individual balancing networks adapted to balance said line and said auxiliary apparatus, and normally effectively connected with said repeater circuit, switching relays associated with said auxiliary balancing networks adapted to be energized by the disconnection of the auxiliary apparatus, and means to prevent the energization of the said relays when similar apparatus has been connected with the said line to replace the apparatus effectively disconnected from the said line.
10. 2. In a telephone transmission system, the combination of two transmission circuits, a repeater circuit for operatively connecting together said transmission circuits, auxiliary apparatus associated with each of said transmission circuits, networks associated with said repeater to balance each of said transmission circuits, auxiliary networks associated with said repeater to balance said auxiliary apparatus, switching means associated with said auxiliary networks adapted to be energized by the disconnection of its corresponding auxiliary apparatus, and means to prevent the energization of the said relays when similar apparatus has been connected with the said line to replace the apparatus effectively disconnected from the said line.
15. 3. In a telephone transmission system the combination of a phantom group comprising two physical circuits and a phantom circuit, auxiliary apparatus associated with said physical circuits, a telephone repeater connected with each of said circuits, networks associated with each repeater to balance the circuits associated therewith, auxiliary networks associated with each repeater to balance the auxiliary apparatus of the circuits associated therewith, and switching means adapted to be energized by the disconnection of said auxiliary apparatus, whereby a balancing network corresponding to said auxiliary apparatus may be effectively disconnected from the said repeater whenever the auxiliary apparatus is disconnected from the line circuit.
20. 4. In a telephone transmission system, the combination of a phantom group comprising two physical circuits and a phantom circuit extending in one direction, a corresponding group extending in another direction, a group of telephone repeaters adapted to connect the corresponding physical and phantom circuits of each of said phantom groups, auxiliary apparatus associated with said physical circuits, networks associated with each repeater to balance the circuits connected thereto, auxiliary networks associated with each repeater to balance the auxiliary apparatus of the lines connected thereto, and switching means associated with the auxiliary networks whereby the said auxiliary networks of a physical circuit and of a phantom circuit may be disconnected from the said repeater whenever the corresponding auxiliary apparatus is disconnected from a physical circuit.
25. 5. In combination with a transmission line, an auxiliary apparatus associated therewith, a balancing arrangement therefor comprising an artificial line simulating the transmission line, an auxiliary balancing set for simulating the auxiliary apparatus, switching means designed to render the auxiliary balancing set inoperative at will and means to prevent the rendering of the said balancing set inoperative whenever the said auxiliary apparatus is replaced by similar apparatus.
30. 6. A balancing arrangement comprising an artificial line for simulating a transmission line, an auxiliary balancing set for simulating the auxiliary apparatus associated with a transmission line, switching means controllable at will, adapted to disconnect said artificial line from the balancing arrangement, and means to prevent the said disconnection whenever said auxiliary apparatus is replaced by similar apparatus.
35. In testimony whereof we have signed our names to this specification this 8th day of July, 1919.
